THOMAS F. F. LEE, OF BROOKLYN, NEW YORK, ASSIGNOR TO GERTRUDE M. LEE, OF NEW YORK, N. Y.

FURNACE.

1,275,986.

Specification of Letters Patent. Patented Aug. 13, 1918.

Application filed September 28, 1906, Serial No. 336,629. Renewed January 18, 1918. Serial No. 212,535.

To all whom it may concern:

Be it known that I, THOMAS F. F. LEE, citizen of the United States, residing at borough of Brooklyn, in the county of Kings and State of New York, have invented a new and useful Furnace, of which the following is a specification.

My invention relates to down-draft furnaces, and consists in a furnace of new construction and mode of operation, involving new proportions of parts, whereby a strong natural draft is created, promoting the combustion, and the combustion so increased reacts to increase the draft, whereby a high degree of heat is generated with practically perfect combustion of the fuel, the gases and the smoke.

The essential features of my furnace are the fuel receptacle of brick-work or other refractory material forming the outer, or solid fuel, combustion chamber, into which the solid fuel is fed from above automatically, by gravity or other means, so as to pass down through channels on each side of the boiler to the outer combustion chamber. The boiler is preferably of the horizontal tubular style having an inner, or gas combustion, chamber extending throughout its entire length, in its lower portion, and almost surrounded by water spaces. The edges of the water spaces below do not meet, but leave a longitudinal opening, which may extend from end to end. Practically speaking only the front portion of this opening is operative in promoting combustion, for that front portion forms a contracted bottom opening between the outer, and the inner, combustion chambers, extending back to the end of the fire-box where it is closed by the solid brick-work base, or foundation, on which the boiler rests. The proportions of the various openings, chambers and flues hereinafter described in detail are also an important part of my invention.

My invention also lies in the various details of construction and arrangement of the parts of the boiler, of the grates, of the auxiliary flues, side grates and in the means for supporting parts, and the method of supplying the air.

My invention is shown in a desirable form

in the drawing herewith, in which the reference letters and numerals of the specification indicate the same parts in all the figures. Figure 1 is the vertical cross section of the furnace, shown partially in elevation. Fig. 2 is a vertical longitudinal section, with portions of the farther side broken away. Fig. 3 indicates the arrangement of the boilers in a battery.

In the figures, 1 indicates the brick-work supporting the boiler and forming at the front end the outer combustion chamber 2, to which the fuel is fed down through the down-draft channels 3, on the sides of and at the front end of the boiler 4. These channels may be closed more or less by dampers 5, to regulate the draft and to hold back the fuel, and the fuel may be delivered thereto through a hopper 6 and chutes 7. If desired, the side walls may be extended up and above the boiler, and the fuel fed in and burned on top and all around it, thereby producing superheated steam.

From this description it will be understood that the fuel-containing walls confine the passage of the combustion supporter and the combustion gases before and during at least a substantial portion of their travel through the combustion chamber and the fuel bed so that they percolate between the solid lumps and particles of the fuel.

In the lower portion of the boiler, the inner shell 10 forms the inner, or gas combustion, chamber 11 communicating with the tubes 13 through the rear chamber 14 and communicating with the outer chamber through the front portion of the longitudinal opening, which is called herein the slot, and this front portion (extending to about the firing line 16) is the only portion of the bottom opening that is functionally operative; as back of the fire-box it is nearly closed by the solid brick-work foundation on which the boiler rests. The boiler may be raised above the solid brick-work, as on short piers, so as to leave a slight space of an inch or two between the boiler and the brick bed foundation which permits access of the heat and gases directly to the exterior of the water spaces surrounding the legs without interfering with the important

suction draft through the main opening or slot.

The arrangement of the grates at the side and bottom of the outer combustion chamber and the air orifices as shown, are auxiliary, this being essentially a down-draft furnace in which the main draft is down through the fuel in the side channels; but by the use and application of the grates, the 10 air is more thoroughly mixed with the gases generated, and they are progressively heated as they rush down through the fuel and through the contracted slot into the inner chamber, where they are consumed almost 15 explosively with intense heat. Said grates and the two sets of auxiliary side flues operate in regulating the draft for different conditions of temperature and atmosphere, different kinds of fuel, and for shaking down 20 the coke or carbon formed in the upper levels where the gases and volatile substances are generated, and insuring complete consumption thereof.

To assist the traveling movement of the 25 fuel through the combustion chamber; and over the solids-discharging grate various means have been provided. The inclination of the combustion chamber forms one such means, for it is the inclination of the combustion chamber at an angle from the horizontal that causes the fuel to tumble down toward the discharging grate. At the discharging grate additional means are used to 30 secure the traveling movement of the fuel 35 and to insure its complete combustion.

To this end I provide an ash-pit 25 having clean-out doors 26, to which a limited amount of air may controllably be admitted through the two series of small, inclined, 40 lower flues, or inlets, 28, having dampers 29, under the grate, composed of grate-bars 27 carried on racks 30 and having drop rods 31, at the front, respectively connected on each side to connecting bars 32 having straps 45 33 connecting them to the main lever 34, provided with a shaker-bar 35, supported in hanger 36 and outwardly extending through the doors 26, for the shaker handle. Any other suitable means may be provided for 50 moving or rocking the bars toward the center, to shake down the ashes; but it should be observed that owing to the perfect combustion obtained through the new principle herein involved, there will be no clinkers 55 and merely the ash, or silicon, the coal or fuel contains, which accumulates on the burning coke or carbon in the form of a white ash or powder, easily shaken off by rocking the grates, thereby permitting and 60 continuing the combustion of the coke or carbon.

This grate provides an area for discharging solids, or for discharging the refuse from the fuel during and after combustion. It is 65 apparent, of course, that some means to dis-

charge coke may be employed and thus the furnace kept in continuous operation without clogging.

The side air chambers 40 40 having the upper auxiliary flues 41 provided with the 70 dampers 42 controlling the admission of air, and the inclined side grates 43 covering said chambers, are to insure the uniform burning of the fuel across the entire width of the channels, and to avoid any 75 danger of the coal lying dead against the outer surfaces of the channels. The air entering through these upper inlets into the side chambers is distributed through the entire length of the chamber and passes 80 through the side grates at all points.

Air enters the fuel bed between the lumps and particles of the fuel and in doing so enters the fuel bed in a plurality of streams. This division of the entering air into a 85 plurality of streams is facilitated by the plurality of inlets between the grate bars.

In order to secure a continually operated furnace, air must enter in quantities sufficient for the combustion of the fuel while 90 traveling. A very slow amount of air entering through the side grates might, in time, if the fuel was stationary cause a fire to creep up through the combustion chamber, even to the top of the chamber; but in 95 this case the fire might become extinguished at the bottom of the combustion chamber, and the chamber might become so clogged as to finally destroy its method of operation.

By "quantities sufficient for combustion 100 of the fuel while traveling" I mean, quantities sufficient to cause the fire to burn up to the air inlets while the fuel is advancing at the normal or adjusted rate through the combustion chamber, maintaining combustion 105 all the time at or near the inlets through the side grates.

If the air is insufficient for this purpose the fuel in traveling downward (in case there was enough draft at the bottom of 110 the combustion chamber) would carry along with it the limit of the fire; or, if the inlets of air over the whole grate surface, side and bottom, was cut down to a small degree then, since the fuel would remain nearly 115 stationary, the fire might travel slowly up to the top of the chamber and away from the bottom, as hereinbefore referred to.

The successful operation of this feature of the combustion chamber is largely dependent upon the admission of air through the wall grates in quantities sufficient to cause the fire to travel upward as rapidly as the fuel is traveling downward.

It will be seen that the inlets in the wall 125 grates are divided into two zones by the brick work of the walls of the furnace. There is an upper zone above the brick work and a lower zone below the brick work. To each zone air is admitted through a con- 130

duit terminating in the dampers. Each conduit leads to a plurality of inlets between the grate bars so that a variation of the adjustment of the dampers varies the amount of air passing through the conduits and through the inlets between the grate bars of the zone controlled by such dampers.

Since there is an upper and lower conduit it is thus possible to adjust the air admitted

10 through them both in quantities sufficient for the combustion of the fuel and maintain the combustion of the fuel during its traveling movement toward the discharging grate.

15 The resistance to the passage of air through the upper dampers, conduit and grate inlets is naturally greater than the resistance through the lower conduit and inlets since the air has to pass through a longer bed of fuel. This must be compensated for by decreasing the supply of air entering the lower dampers and allowing it freer access through the upper dampers. In this way the smaller resistance of the 20 fuel bed to the passage of air entering through the lower dampers is compensated for.

The upper and lower dampers may be so adjusted as to secure fire at any level in 30 the combustion chamber that may be desired. The maximum operation of the furnace results from such an adjustment with sufficient air admitted through both conduits to completely burn the fuel when traveling at its fastest rate (which, of course, is slow), through the combustion chamber; and when the dampers are so adjusted as to have the zone of combustion extend from the discharging grate well up into the combustion chamber along the inlets through the wall grates connecting with the upper 40 conduit, best results are secured.

It is obvious that the lower conduit and dampers also regulate the air admitted 45 through the discharging area or opportunity for becoming united with unconsumed oxygen or air or combustion supporter (the term combustion supporter being intended to cover any form of gases, air, steam or 50 whatnot that may be employed as an element in supporting combustion).

The pressure of the atmosphere upon the gases upon the combustion chamber side of the furnace tend to press them forward 55 through the slot or opening; and the rarefaction of the burned gases due to heat and to their lighter specific gravity, and their tendency to escape upward results in a tendency toward a partial vacuum, that is, 60 a slight drop in pressure, affecting the gases in the inner combustion chamber and expedites their passage through this inner combustion chamber, through the tubes and up the stack.

65 Since more air is admitted through the

discharging grate, than is required for the coke which is being burned there, this air becomes highly heated in the presence of the incandescent coke; and as it passes on through the slot and into the inner combustion chamber its chemical affinity for carbon and hydro-carbon matters is increased and this facilitates complete combustion.

It has been found that the gases issuing 75 from the surface of the fuel bed, adjacent to the slot, contain a considerable percentage of CO. The additional oxygen supplied through the discharging grate converts these CO gases and the coke into CO₂ gases, 80 thereby liberating the maximum amount of heat from the coal.

As a matter of fact, the degree of temperature attained in the inner combustion chamber and at the opening is very much 85 higher than that of the ordinary furnaces; and this degree of heat is largely dependent upon confluent streams of combustion gases, containing a considerable percent. of CO gases from the fuel bed, and a considerable 90 percent. of heated and uncombined oxygen entering through the discharging grate. Their confluence at the slot or opening intimately unites the grate and the description heretofore applied to the lower wall grates 95 applies also to the discharging grate, adjustment of the dampers with regard thereto and to the air entering through the discharging grate.

The discharging grate may be so arranged as to secure the discharge of solids or coke, if desired, at the lower end of the combustion chamber and particularly to facilitate the discharge of ashes. This discharging function is essential where it is 100 desired to keep the lower end of the combustion chamber free from any accumulation of solid matter.

Hinged at the lower edges of the side grates, are the comb-grates 46 whose lower 110 edges rest freely on lugs 47 on the outer grate-bar surface, so that when the grate-bars are rocked the comb-grates are also slightly rocked (or they can be rocked independently) to insure the descent of the coke 115 and to prevent it clogging on the sides. When the furnace is in operation, no fresh coal, or fuel, reaches either the lower grate bars, or the comb-grates, as all the free gases and volatile portions of the fuel are drawn 120 out in the upper levels leaving only the coke or carbon to descend to the comb-grates, or the bottom grates, where it is consumed, while the gases so generated are sucked down through this bed of fuel and 125 into the combustion chamber becoming superlatively heated, and thoroughly mixed so that when combustion is at its height, the free gases and the volatile portions of the fuel are being mixed and intermingled with 130

the burning products of the coke, and all thoroughly admixed with air, admitted through the various openings, resulting in an extraordinary degree of heat. The air admitted through the lower inlets should be sufficient to insure the final and complete consumption of the coke or carbon, and any unburned portions of the volatile gases that may be drawn down from above, and 10 no more.

50 indicates diaphragm plates extending through nearly the entire length of the water legs 17 and arranged substantially perpendicularly to the inner and outer 15 shells. The space a between the front end of each plate and the end of the boiler is preferably slightly greater than the corresponding space b at the rear. As the greatest heat is applied directly to the front 20 portion of the boiler, the generated steam rushes up through the front spaces a creating a circulation of the water up through the front spaces, and therefore down through the rear spaces b , the front 25 spaces being preferably larger, as aforesaid, giving the water a freedom of access up in front and checking it somewhat in the rear, thereby insuring and promoting circulation, which is further promoted by the injection 30 of the feed water through the pipes 51, on both sides of the channels and under the plates; so that the water is first heated as it passes across the rear chamber, and then continuously heated in said channel as 35 it flows toward the front, where it is rapidly converted into steam economically and at the most desirable points. These plates also reinforce the water legs and are a substantial aid to the construction of the boiler, 40 besides producing circulation therein, and preventing the accumulation of dust or sediment.

55 is the short stack, 56 and 57 are rear doors, for access to the rear chamber, the 45 inner combustion chamber and the main opening; 58 is a front door to the outer combustion chamber; 59 and 60 indicate respectively the usual drum and one or more steam pipes therefrom; 61 are hand-hole 50 doors to the water-legs; and 62 is the rear head. The boiler is desirably reinforced and braced by braces 63 radiating from the inner shell 10 to the outer shell 65.

Fig. 3 is a diagram showing how my invention may be adapted to a battery of 55 boilers. Front openings 70 are provided in the brick-work to admit the air to the side chambers 40, and flues 71 to admit the air to the lower inclined flues 28. Said front 60 openings and flues may be provided with suitable doors or dampers.

An important feature of my invention is the proper proportion of the front portion of the contracted main opening, or slot, to 65 the inner combustion chamber. The width of

this main opening should not be more than one-half the diameter of the inner combustion chamber, nor less than one-quarter of said diameter. From one-quarter to one-third is desirable. For long boilers it 70 should be narrower and longer, and for short boilers shorter and wider, thereby providing the proper length of fire box necessary for longer or shorter boilers. But the total area of the front employed portion 75 of the main opening, or slot should not be substantially more than the working area of the cross section of the inner combustion chamber. By working area I mean the area of the inner combustion chamber which may 80 also be termed an auxiliary chamber or a collecting and distributing chamber, together with the area of that portion of the slot or opening at the bottom of the boiler back of the firing line, 16, which may 85 not be filled up with brick. For this purpose the free portion of the opening may be considered as part of the inner chamber. In other words, the slot is substantially 90 equal in area, to the cross section of the inner chamber. I have spoken of the "slot," or operative front portion of the main opening into the inner combustion chamber, and it is therefore evident that said opening 95 may be closed back of the firing line, but it 95 is shown extending to the rear end of the boiler, because easier to construct.

Among the functions of the inner combustion chamber is that of facilitating complete combustion. The combustion gases issuing from the fuel bed pass into the slot or opening at the bottom of the boiler and into the inner combustion chamber. In passing through the slot or opening they are brought into more intimate contact which 100 intensifies combustion; and as they pass into the combustion chamber they spread out again through the chamber and have a further opportunity to become more completely intermingled, and all particles of 105 carbon and of unconsumed gaseous matter are provided with further streams of combustion supporter, resulting in the high degree of heat, heretofore described.

One set of proportions which I have 115 found useful is as follows:

A tubular boiler having eighty or ninety tubes each about three inches in diameter; a fire box five feet long and a slot running the 120 length of the boiler but open at the fire box five feet of its length. The area of the slot or opening is therefore four hundred and eighty square inches. The area of the eighty tubes is about the same; possibly fifteen per cent. greater to allow for friction, etc.

The cross sectional area of the inner combustion chamber is approximately the same as the area of the slot or opening. It will be noted that the gases issuing from the sur- 130

face of the fuel in the combustion chamber are flattened out in a ribbon-like stream in the opening, and as they pass into the inner combustion chamber to the rear of it they 5 are given a circular cross section.

By this change in the cross sectional form of the gases as they pass from one portion of the furnace to another through substantially equal areas, the gases are more intimately mixed, and the various portions thereof are shifted with relation to each other and more intimately intermingled which facilitates complete combustion.

The pressure of the atmosphere at the fuel 15 combustion chamber end of the furnace and the lighter specific gravity of the gases in the stack establish a draft through the furnace and cause the gases to pass through the tubes of the boiler at the speed requisite 20 for the service desired therein.

The speed may be increased and the output of the boiler thereby increased at the cost of economy. That is, the gases may issue from the boiler at a higher temperature 25 and escape up the stack; or the gases may pass through the boiler at a lower speed and issue at a lower temperature from the tubes thereby increasing the economical efficiency of the furnace.

30 From the foregoing description it will appear that some very important factors and principles of furnace construction have been developed. The quantity of fuel fed to the combustion chamber during normal 35 operation in a given period of time, and the amount of combustion supporter supplied to it are adjusted to the capacity of the boiler with regard to its heat absorbing qualities.

Since the amount of heat absorbed by a 40 boiler depends upon the period of time that the heated gases take in passing through the boiler, and since this factor depends upon the height of the stack, and since the controlling area of the slot and of the inner 45 combustion chamber affect these factors, it follows that for any given power output at any efficiency these various factors have substantially a certain adjusted relation to each other. Through the combustion chamber, 50 the combustion gases should pass at such a speed as will thoroughly burn and take up the combustible elements of the fuel. Through the slot they should pass at such a speed as will most intimately intermix 55 them without interfering with their passage to such an extent as to cut down the desired draft. Through the auxiliary combustion chamber 11 they should pass at a speed sufficient to furnish further facilities 60 for intimate union without interfering with the necessary speed or passage. Through the tubes of the boiler they should pass at such a speed as will permit them to give up the desired amount of heat units contained 65 therein. Through the boiler and through

the stack they should pass at such a speed, and over such a distance, as will enable the foregoing functions to be performed.

If the inlets to the combustion chamber are too small in their gross area, the normal 70 operation of the furnace is affected proportionately. If the area of the slot or opening is disproportionately small, the volume of the gases passing through the passageways of the furnace is reduced. The same would 75 be true if the area of the inner combustion chamber beyond the fire line should be disproportionately small.

If the gross area of the tubes of the gas 80 passageways in the boiler is disproportionately small, the volume of gases passing through the boiler is proportionately diminished and the power output correspondingly reduced. This factor also reduces the efficiency of the whole apparatus. 85 The combustion chamber, the fuel bed, the inlets for air, the opening or slot, the inner combustion chamber might then all be correspondingly reduced and get as good results. That is, a reduction in the tube area 90 renders unnecessary the proportionately large size of all these other factors, and their unnecessary cost of construction.

If the stack has too small a cross-sectional area it has the result of cutting down 95 the volume of gases traveling through the gas passageways of the furnace within a given period of time, and results in a sluggish movement thereby cutting down the efficiency of the apparatus and interfering 100 materially with the character of the combustion.

This factor also reduces the efficiency of the apparatus by reason of the sluggish movement of the gases through the passageways of the boiler; and the degree of smoky combustion is dependent upon the degree to which the stack area may be reduced below the normal requirements of the furnace.

If the cross sectional area of the stack is 110 sufficiently reduced, more or less smoke will appear. If the stack is restored to its proper adjusted area, smoke disappears.

The comments in regard to the area of the stack are also applicable to its height; 115 and a reduction of the height would have the same general defects that are produced by reduction of the cross sectional area.

If the inlet areas of the fuel combustion chamber are increased, the volume of burning fuel is diminished and the level to which combustion extends up the combustion chamber is lowered proportionately, resulting in a volume of combustion products unnecessarily diluted by air and correspondingly decreased in temperature.

If the areas are increased far enough, smoke will result.

If the area of the slot or opening to the inner combustion chamber is disproportion-

ately increased, particularly in width, its function in creating a more intimate union of the confluent streams of combustion gases will be correspondingly lost.

5 The consequent factors are, a lowering of temperature throughout the apparatus, including a combustion chamber; a lowering of the power output of the apparatus; a lowering of the stack temperatures and a 10 consequent reduction of draft, and, if carried far enough, smoky combustion.

The increase in the cross sectional area of the inner combustion chamber will have the effects of permitting an unnecessary expansion of the gases therein, reducing their speed of travel therethrough, of cutting down their temperatures therein and consequently of cutting down the temperatures of the gases entering the tubes of the boiler 20 and passing up the stack, which results in a reduction of the draft which may be compensated for by a corresponding increase in the height of the outlet.

An increase in the gross cross sectional 25 area of the tubes produces the result that the gases spread out more in the tubes, and passing more slowly through, cool off to a greater degree. This results in lower stack temperatures and a general reduction of the 30 draft of the furnace and loss of efficiency.

This effect may be somewhat offset by increasing the stack to such an extent as will bring the gases through the tubes of the boiler at the required temperature; though 35 this method of correcting the trouble would be a makeshift and result in an apparatus unnecessarily large for a given power output.

An increase in the height or area of the 40 stack within certain limits would have the result of pulling the combustion gases through the tubes of the boiler at a more rapid rate, and this would have the result of bringing them to the stack at a higher temperature. It would also result in an increase 45 of the air entering the combustion chamber. This increase of air would dilute the combustion gases and reduce their temperature so that as they passed into the tubes of the 50 boiler they would give up less heat.

From this it appears that an increase in the height or area of the stack, within certain limits, will cut down the economy of the furnace and may even be carried far enough 55 to effect efficiency.

There is a limit of height or area, or both for the stack beyond which it loses many of its desirable functions.

From the foregoing description it will appear 60 that applicant's furnace contains some new adjustments of the different parts to each other by means of which substantially complete combustion and the highest efficiency obtainable may be secured.

65 The apparatus may be designed to give

the greatest economy from full consumption; or it may be designed to give the maximum power output for a given size furnace, regardless of economy. In practice usually, the furnaces are designed to secure the most 70 practical economy.

From the foregoing description it will appear very clearly that the air admitted to the combustion chamber is regulated by a combination of different factors. First, the 75 character of the fuel, that is, the size of the lumps, and the area of the passageways between them which regulates the amount of air entering through the top of the combustion chamber; second, the area of the inlets 80 which causes the air entering to any particular zone of inlets to be distributed or pass over the whole surface of the zone, and third, the dampers 29 and 41 which regulate the amount of air admitted to the different zones 85 of inlets.

To insure perfect operation the outflow of the draft of air from the inner combustion chamber should be free and unimpeded. To this end, the rear chamber should be of sufficient size to permit the combustion products to pass and reverse freely to the flues or boiler tubes. The total cross sectional area of the tubes should be somewhat larger, possibly fifteen per cent. than the total area of 95 the slot or opening to allow for friction, accumulation of dust, etc., in the tubes. The stack 55, should be, if anything, a little larger than a cross section area of the flues. In this boiler, the stack is a mere outlet and 100 is not functionally important as contributing to the draft above the point where the escaping gases cool to the temperature of the surrounding atmosphere; and as the stack products are composed principally of nitrogen and CO₂, which cool rapidly if forced or carried higher than this point, because of the high specific gravity, particularly of the CO₂, they act as a retard or weight upon the induction draft created at the slot or main 105 opening into the combustion chamber, so that a high stack is impracticable and undesirable. The total cross sectional tube area, when determined, thus practically determines the area of the inner combustion 110 chamber, and the main slot or opening. 115

By the new principle involved, practically perfect combustion of the fuel is obtained, destroying and utilizing smoke, gases and solid portions thereof, generating a very 120 high temperature with its application to the water in the exposed portion of the boiler initially at the most important points throughout its entire length.

Another feature of this furnace is the total 125 elimination of all crust, scale, deposit or otherwise in the tubes or other exposed portions of the boiler so that at all times, the heat and gases impinge directly upon the naked iron, thereby greatly increasing the 130

life and efficiency of the boiler and the action of said heat upon the water surrounding the said flues and exposed portions thereof.

5 Having thus described my invention, what I claim as new and desire to secure by Letters Patent, is:—

1. In a fuel burning apparatus, a combustion chamber through which the fuel is given a traveling movement; said combustion chamber having fuel confining walls, a refuse discharging area and a gas outlet for the escape of products of combustion, means to substantially confine the combustion supporter and gases to the body of the fuel and to cause them to travel in the direction of movement of said fuel to the said outlet and discharging area, means for feeding the combustion supporter in regulable quantities to the fuel at intervals along the path of movement thereof, the quantities of the said fuel and of the combustion supporter being so regulated and proportioned relative to each other that the fuel is substantially completely burned.

2. In a fuel burning apparatus, a combustion chamber through which the fuel is given a traveling movement, said combustion chamber having fuel confining walls, a refuse discharging area, and an outlet for the products of combustion; means to cause said products to travel through the fuel bed and through said chamber in the general direction of movement of said fuel, means for distributing the combustion supporter in regulated quantities to the fuel at intervals along zones of combustion, the quantities of said fuel and combustion supporter being so regulated and proportioned relative to each other that the fuel is substantially completely burned.

3. In a fuel burning apparatus, a combustion chamber through which the fuel is given a traveling movement said combustion chamber having fuel retaining walls, a refuse discharge area and a gas outlet for the products of combustion; means to cause the said products of combustion to move through the fuel bed and the combustion chamber in the general direction of movement of said fuel to the gas outlet, means for feeding the combustion supporter to said fuel bed in regulated quantities to zones located at intervals along the path of movement thereof, the quantities of said fuel and of the combustion supporter being so regulated, distributed, and proportioned relative to each other that the fuel is substantially completely burned.

4. In a fuel burning apparatus, a combustion chamber through which the fuel is given a traveling movement said combustion chamber having fuel retaining walls, a refuse discharge area and a gas outlet for the products of combustion, means to move

said products of combustion through the said fuel through the combustion chamber in the same general direction to the gas outlet, means for supplying the combustion supporter to said moving fuel in regulated quantities, at intervals along the path of movement thereof, the quantities of said fuel and of the combustion supporter being so regulated and proportioned and distributed relative to each other that the solid fuel and CO gases are substantially completely burned; and means to vary the quantity of combustion supporter supplied to each zone.

5. In a fuel burning apparatus, a combustion chamber through which the fuel is given a traveling movement, said combustion chamber having fuel confining walls and a refuse discharging area, a wall of the combustion chamber having an opening for the escape of products of combustion, means to substantially confine the combustion supporter and gases to the body of the fuel and to cause them to travel in the direction of movement of said fuel to the said opening and discharging area, means for feeding the combustion supporter in regulable quantities to the fuel at intervals along the path of movement thereof, the quantities of the said fuel and of the combustion supporter being so regulated, distributed, and proportioned relative to each other that the fuel is substantially completely burned; said gas outlet being constricted in area to coöperate with and assist the flow of gases from said combustion chamber.

6. In a fuel burning apparatus, a combustion chamber through which the fuel is given a traveling movement, said combustion chamber having fuel confining walls, a refuse discharging area and an outlet for the products of combustion; means to cause them to travel through the fuel bed and through said chamber in the general direction of movement of said fuel, means for distributing the combustion supporter in regulated quantities to the fuel at intervals along the path of combustion, the quantities of said fuel and combustion supporter being so regulated and proportioned relative to each other that the fuel is substantially completely burned, said outlet being constricted in area to regulate the required flow of gases from said combustion chamber.

7. In a fuel burning apparatus, a combustion chamber through which the fuel is given a traveling movement, said combustion chamber having fuel confining walls, a refuse discharge area and a gas outlet for the products of combustion; means to cause the said products of combustion to move through the fuel bed and the combustion chamber in the general direction of movement of said fuel to the gas outlet, means for supplying the combustion supporter to said fuel in regulated quantities along zones,

at intervals along the path of movement thereof, the quantities of said fuel and of the combustion supporter being so regulated and proportioned relative to each other that the fuel is substantially completely burned; said gas outlet being constricted in area to regulate the required flow of gases from said combustion chamber.

8. In a fuel burning apparatus, a combustion chamber through which the fuel is given a traveling movement said combustion chamber having fuel confining walls, a refuse discharge area and a gas outlet for the products of combustion; means to move said products of combustion through the said fuel bed and through the combustion chamber in the same general direction to the gas outlet, means for supplying the combustion supporter to said moving fuel in regulated quantities to zones located at intervals along the path of movement thereof, the quantities of said fuel and of the combustion supporter being so regulated and proportioned relative to each other that the fuel is substantially completely burned; and means to vary the quantity of combustion supporter supplied to each zone; said gas outlet being constricted in area to regulate the required flow of gases from said combustion chamber.

9. In a fuel burning apparatus, a boiler having tubes, a combustion chamber through which the fuel is given a traveling movement, said combustion chamber having fuel confining walls, a refuse discharging area and a gas outlet for the escape of products of combustion; means to substantially confine the combustion supporter and gases to the body of the fuel and to cause them to travel in the direction of said fuel movement to the said opening and discharging area, means for feeding the combustion supporter in regulable quantities to the fuel at intervals along the path of movement thereof, the quantities of the said fuel and of the combustion supporter being so regulated and proportioned relative to each other that the fuel is substantially completely burned; said boiler tubes having a combined area sufficient to allow the free passage of gases from said outlet.

10. In a fuel burning apparatus, a boiler having tubes, a combustion chamber through which the fuel is given a traveling movement, said combustion chamber having fuel confining walls, a refuse discharging area, and a gas outlet for the products of combustion, means to cause them to travel through the fuel bed and through said chamber in the general direction of said fuel movement, means for distributing the combustion supporter in regulable quantities to the fuel, at intervals along the path of combustion, the quantities of said fuel and combustion supporter being so regulated

and proportioned relative to each other that the fuel is substantially completely burned; said gas outlet being constricted in area to regulate the required flow of gases from said combustion chamber, said boiler tubes having a combined area sufficient to allow the free passage of gases from said outlet.

11. In a fuel burning apparatus, a boiler having tubes, a combustion chamber through which the fuel is given a traveling movement, said combustion chamber having fuel confining walls, a refuse discharge area and a gas outlet for the products of combustion; means to cause the said products of combustion to move through the fuel bed and the combustion chamber in the general direction of movement of said fuel to the gas outlet, means for supplying the combustion supporter in regulated quantities to the fuel at intervals along the path of movement thereof, the quantities of said fuel and of the combustion supporter being so regulated and proportioned relative to each other that the fuel is substantially completely burned; said boiler tubes having a combined area sufficient to allow the free passage of gases from said outlet.

12. In a fuel burning apparatus, a boiler having tubes, a combustion chamber through which the fuel is given a traveling movement, said combustion chamber having fuel confining walls, a refuse discharge area and a gas outlet for the products of combustion; means to move said products of combustion through the said fuel bed and through the combustion chamber in the same general direction to the gas outlet, means for supplying the combustion supporter to said moving fuel in regulated quantities at intervals along the path of movement thereof, the quantities of said fuel and of the combustion supporter being so regulated and proportioned relative to each other that the fuel is substantially completely burned, and means to vary the quantity of combustion supporter supplied at the various intervals; said gas outlets being constricted in area to regulate the required flow of gases from said combustion chamber, said boiler tubes having a combined area sufficient to allow the free passage of gases from said outlet.

13. In a fuel burning apparatus, a boiler having tubes, a stack, and a combustion chamber through which the fuel is given a traveling movement, said combustion chamber having fuel containing walls, a refuse discharging area and an outlet for the escape of products of combustion; means to substantially confine the combustion supporter and gases to the body of the fuel and to cause them to travel in the direction of the movement of said fuel to the said outlet and discharging area; means for supplying the combustion supporter in regulable quan-

- ties to the fuel at intervals along the path of movement thereof, the quantities of the said fuel and of the combustion supporter being so regulated and proportioned relative to each other that the fuel is substantially completely burned; said gas outlet being constricted in area to regulate the required volume of gases from said combustion chamber, said boiler tubes having a combined area sufficient to allow the free passage of gases from said outlet, said stack being proportioned in its area and height to create the required movement of gases through said furnace and boiler tubes.
- 15 14. In a fuel burning apparatus, a boiler having tubes, a stack; and a combustion chamber through which the fuel is given a traveling movement, said combustion chamber having fuel confining walls and a refuse discharging area, an exit opening in said chamber for the products of combustion, means to cause them to travel through the fuel bed and through said chamber in the general direction of movement of said fuel, 20 means for distributing the combustion supporter in regulable quantities to the fuel along the zone of combustion, the quantities of said fuel and combustion supporter being so regulated and proportioned relative to each other that the fuel is substantially completely burned; said gas outlet being constricted in area to effect the proper flow of gases through said combustion chamber, said boiler tubes having a combined area 25 sufficient to allow the free passage of gases from said outlet, said stack being proportioned in its area and height, to move the required volume of gases at a required velocity through said furnace, gas outlet and boiler tubes.
- 30 15. In a fuel burning apparatus, a boiler having tubes, a stack, and a combustion chamber through which the fuel is given a traveling movement, said combustion chamber having fuel confining walls, a refuse discharge area and a gas outlet for the products of combustion, means to cause the said products of combustion to move through the fuel bed and the combustion chamber in the general direction of movement of said fuel to the gas outlet, means for supplying the combustion supporter to said fuel bed in required quantities along the path of movement thereof, the quantities of said fuel and of the combustion supporter being so regulated, proportioned and distributed relative to each other that the fuel is substantially completely burned; said boiler tubes having a combined area sufficient to allow the free 35 passage of gases from said outlet, said stack proportioned in its area and height to efficiently coöperate with all parts of said fuel burning apparatus.
- 40 16. In a fuel burning apparatus, a boiler having tubes, a stack, a combustion chamber through which the fuel is given a traveling movement, said combustion chamber having fuel confining walls, a refuse discharge area and an outlet for the products of combustion; means to cause the said fuel and products of combustion to move through the combustion chamber in the same general direction to the gas outlet, means for feeding the combustion supporter to said moving fuel bed in quantities so regulated as to effect a proper admixture of same, at intervals along the path of movement thereof, the quantities of said fuel and of the combustion supporter being so regulated and proportioned, relative to each other that the fuel is substantially completely burned, and means to vary the quantity of combustion supporter supplied; said gas outlet being constricted in area to effect the flow of the required volume of gases through said combustion chamber; said boiler tubes having a combined area sufficient to allow the free passage of gases from said outlet, and said stack so proportioned in its area and height as to effectually co-operate with the other essential parts of said fuel burning apparatus.
- 45 17. In a fuel burning apparatus, a combustion chamber having fuel retaining walls, containing a refuse outlet, an outlet for the gaseous products of combustion, located in the neighborhood of said refuse outlet, an inlet for supplying fuel and inlets for the supplying of combustion supporter; means to cause the fuel, combustion supporter and gaseous products of combustion to move in the same general direction, as a substantially commingled body of solid and gaseous matter, from the supplying sources of both to said refuse and gas outlets, means to so distribute the combustion supporter to said fuel column, from the fuel supply source to and through the refuse discharging area, that the decreasing solid carbon content of the fuel column and the increasing volume of gaseous products are constantly supplied with combustion supporter, each in the quantity required for substantially complete combustion.
- 50 18. In a fuel burning apparatus, a combustion chamber through which the fuel is given a traveling movement, said combustion chamber having fuel retaining walls, a refuse discharge area and a gas outlet for the products of combustion; means to cause the said products of combustion to move through the fuel bed and the combustion chamber in the general direction of movement of said fuel to the gas outlet, means for supplying the combustion supporter to said fuel bed in regulated quantities at intervals along the path of movement thereof, the quantities of said fuel and of the combustion supporter being so regulated, distributed and proportioned relative to each other that the fuel is substantially completely burned.
- 55 60 65

19. In a fuel burning apparatus, a combustion chamber through which the fuel is given a traveling movement, means for assisting the forward traveling movement of the fuel and ashes in said combustion chamber, said combustion chamber, having fuel retaining walls, a refuse discharge area and a gas outlet for the products of combustion; means to cause the said products of combustion to move through the fuel bed and the combustion chamber in the general direction of movement of said fuel to the gas outlet, means for supplying the combustion supporter to said fuel bed in regulated quantities at intervals along the path of movement thereof, the quantities of said fuel and of the combustion supporter being so regulated, distributed and proportioned relative to each other that the fuel is substantially completely burned.

20. In a fuel burning apparatus, a combustion chamber through which the fuel is given a traveling movement, said combustion chamber having fuel retaining walls, a refuse discharge area and a gas outlet for the products of combustion; one of said walls consisting of a water cooled surface, an auxiliary chamber for the reception of combustion products within it, means to cause the said products of combustion to move through the fuel bed and the combustion chamber in the general direction of movement of said fuel to the gas outlet, means for supplying the combustion supporter to said fuel bed in regulated quantities at intervals along the path of movement thereof, the quantities of said fuel and of the combustion supporter being so regulated, distributed and proportioned relative to each other that the fuel is substantially completely burned.

21. In a fuel burning apparatus, a combustion chamber through which the fuel is given a traveling movement, said combustion chamber having fuel retaining walls, a refuse discharge area and a gas outlet for the products of combustion; one of said walls consisting of a water cooled surface, an auxiliary chamber for the reception of combustion products within it, boiler tubes communicating therewith, means to cause the said products of combustion to move through the fuel bed and the combustion chamber in the general direction of movement of said fuel to the gas outlet, means for supplying the combustion supporter to said fuel bed in regulated quantities at intervals along the path of movement thereof, the quantities of said fuel and of the combustion supporter being so regulated, distributed and proportioned relative to each other that the fuel is substantially completely burned.

22. In a fuel burning apparatus, a combustion chamber through which the fuel is

given a traveling movement, said combustion chamber having fuel retaining walls, a refuse discharge area and a gas outlet for the products of combustion, one of said walls consisting of a water cooled surface, an auxiliary chamber for the reception of combustion products within it, a gas outlet between said combustion chamber and said auxiliary chamber in the neighborhood of the ash discharge area; means to cause the said products of combustion to move through the fuel bed and the combustion chamber in the general direction of movement of said fuel to the gas outlet, means for supplying the combustion supporter to said fuel bed in regulated quantities at intervals along the path of movement thereof, the quantities of said fuel and of the combustion supporter being so regulated, distributed and proportioned relative to each other that the fuel is substantially completely burned.

23. In a fuel burning apparatus, a combustion chamber having fuel retaining walls, containing a refuse outlet, an outlet for the gaseous products of combustion, located in the neighborhood of said refuse outlet, an inlet for supplying fuel and inlets for the supplying of combustion supporter, means to cause the fuel, combustion supporter and gaseous products of combustion to move in the same general direction as a substantially commingled body of solid and gaseous matter, from the supplying sources of both to said refuse and gas outlets, means to so distribute the combustion supporter to said fuel column, from the fuel supply source to and through the refuse discharging area, that the decreasing solid carbon content of the fuel column and the increasing volume of gaseous products are constantly supplied with combustion supporter, each in the quantity required for substantially complete combustion, means for assisting the forward traveling movement of the fuel and ashes in said combustion chamber.

24. In a fuel burning apparatus, a combustion chamber having fuel retaining walls, containing a refuse outlet, an outlet for the gaseous products of combustion, located in the neighborhood of said refuse outlet, one of said walls consisting of a water cooled surface, an auxiliary chamber for the reception of combustion products within it, an inlet for supplying fuel and inlets for the supplying of combustion supporter, means to cause the fuel, combustion supporter and gaseous products of combustion to move in the same general direction as a substantially commingled body of solid and gaseous matter from the supplying sources of both to said refuse and gas outlets, means to so distribute the combustion supporter to said fuel column, from the fuel supply source to and through the refuse discharging area, that the decreasing solid carbon content of

the fuel column and the increasing volume of gaseous products are constantly supplied with combustion supporter, each in the quantity required for substantially complete 5 combustion.

25. In a fuel burning apparatus, a combustion chamber having fuel retaining walls, containing a refuse outlet, an outlet for the gaseous products of combustion, located in 10 the neighborhood of said refuse outlet, one of said walls consisting of a water cooled surface, an auxiliary chamber for the reception of combustion products within it, a gas outlet between said combustion chamber and 15 said auxiliary chamber in the neighborhood of the ash discharge area, an inlet for supplying fuel and inlets for the supplying of combustion supporter, means to cause the fuel, combustion supporter and gaseous 20 products of combustion to move in the same

general direction, as a substantially commingled body of solid and gaseous matter, from the supplying sources of both to said refuse and gas outlets, means to so distribute the combustion supporter to said fuel column, from the fuel supply source to and through the refuse discharging area, that the decreasing solid carbon content of the fuel column and the increasing volume of gaseous products are constantly supplied 25 with combustion supporter, each in the quantity required for substantially complete combustion.

In testimony whereof I have signed my name to this specification in the presence of 30 two subscribing witnesses.

THOMAS F. F. LEE.
